[57] CLAIM

The ornamental design for an electronic calculator with electronic memo, as shown and described.

DESCRIPTION

FIG. 1 is a top plan view of an electronic calculator with electronic memo showing our new design;

FIG. 2 is a bottom plan view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a plan view thereof with cover closed;

FIG. 8 is a front elevational view thereof;

FIG. 9 is a rear elevational view thereof;

FIG. 10 is a right side elevational view thereof; and

FIG. 11 is a left side elevational view thereof.
